UNITED STATES PATENT OFFICE.

BURNHAM C. STICKNEY, OF RUTHERFORD, NEW JERSEY, ASSIGNOR TO UNDERWOOD
TYPEWRITER COMPANY, OF NEW YORK, N. Y., A CORPORATION OF DELAWARE.

TYPEWRITING MACHINE.

Application filed June 6, 1923. Serial No. 643,657.

To all whom it may concern:

Be it known that I, BURNHAM C. STICKNEY, a citizen of the United States, residing at Rutherford, in the county of Bergen and 5 State of New Jersey, have invented certain new and useful Improvements in Type-writing Machines, of which the following is a specification.

The invention relates to a machine for 10 typing upon paper work-webs, comprising several plies, either fan-folded or unattached to each other, and upon each of which plies are usually printed a succession of forms; the form lengths or sections of one 15 ply registering with those of the other plies, and carbons being interleaved with the plies.

The work-webs may be continuous, or of 20 indefinite length, according to the number of forms which compose the same. Ordinarily, however, or at least until so worn as to call for replacement, a fixed length of 25 carbon-sheet is employed; the carbons being shifted, relatively to the work-webs from one form-length to the next succeeding 30 form-length of work-webs when the typing of a form is completed. The usual practice has been; after typing of a form, first, to lift the platen bodily to release the web therefrom and to release the carbons for 35 their shift; then to shift, one form-length rearward, a carbon-carrier with the carbons attached thereto, while holding the work-webs; and then to reset the composite web for commencement of typing on the next 40 form and to replace the platen.

In the co-pending application of Jesse A. B. Smith, Serial No. 640,815, filed May 21, 1923, there is described a machine, operating according to a somewhat different 45 method, for obtaining the same results, and which has certain advantages as to lightness, simplicity and expeditiousness in its manipulation. In this Smith machine, neither the platen nor a carbon-carrier need 50 be shifted in the carbon-shifting operation. The carbons are anchored at their rear, and sufficient slack is provided the composite web between the platen and the anchorage of the carbons to permit writing of a form before such slack is entirely taken up by the line-spacing movements of the platen. After completion of a form, the procedure 55 is: first, to reverse the platen until the carbons are clear thereof and are loose in the

work-webs; a slack in the carbons and work-webs being thus re-established between the platen and the carbon anchorage; then, to rock against the composite web an arcuate table to bend the web until the slack is removed; then, to rotate the platen to shift 60 the work-web a form-length forward while the carbons are held stationary; and then, to return the rocking table to normal position, re-establishing the slack; after which further forward rotary movement of the 65 platen will serve to bring the composite web to position for typing on the fresh form-length, with the slack therein, originally provided.

The present invention relates more particularly to a machine of the general class of the aforesaid Smith machine; and has for its object the provision of means whereby a device, such for instance as the arcuate rocking table of Smith, may be utilized not only to take up the slack in the carbons, preliminary to the shift of the web relatively thereto; but which may also be utilized itself to effect the relative shift of the work-webs and carbons; and which may perform first the one, and then the other, operation in a single continuous movement. In the embodiment of the invention, hereinafter shown, the same comprises means for clamping or holding the work-webs forward thereof after reverse movement of the platen has released the carbons, with the rear ends of the work-webs free (the carbons being then held at their rear ends, and free at their forward ends); and provides for a movement of the rocking table not merely sufficient to take up the slack then in the carbons, but sufficient also to draw the work-webs forward a form-length over the carbons and provide sufficient loose work-web to re-establish the slack or loop.

Other features and advantages will hereinafter appear.

In the accompanying drawings, Figure 1 is a sectional elevation, showing 100 a fragment of the machine seen at Figure 2, the composite web being in position preparatory to typing a fresh form on the web.

Figure 2 is a section, taken longitudinally 105 through the typewriting machine, and showing the position of the parts after the platen has been turned backward to clear the carbons therefrom, preparatory to effecting a

shift of the carbons to a fresh form-length of the work-webs.

Figure 3 is a view showing the position of the parts after such partial movement of the rocking table as is sufficient to take up the slack in the work-webs and carbons.

Figure 4 is a view similar to Figure 3, except that the rocking table has completed its movement, and thereby effected the shift of the carbons.

Figure 5 is a top plan view of the machine, and shows the parts in the position indicated in Figure 2.

Type-bars 10 strike against the front of 15 a revoluble platen 11, which is journaled as usual in a platen-frame comprising ends 12 and a rear paper-shelf 13. The usual reusable feed-rolls 14 run upon the under side of the platen. The platen-frame is 20 mounted upon a carriage 15, which slides along a rail 16 for letter-feeding movements. The platen is rotated line by line by means of the ordinary line-spacing mechanism, comprising a line-space wheel 17.

25 The work-web, usually comprising superposed plies 18 (which may be loose plies or else may consist of a fan-folded web), may be drawn up from a supply-spool or from a zigzag folded pile, which may be contained 30 in a receptacle arranged in rear of the typewriting machine and its stand 21. As the plies of work-web rise from the supply at 19, they pass up through a support or guide, which may comprise a front guide-bar 22

35 and a rear guide-bar 23; these bars spaced sufficiently to accommodate the plies of web confined therebetween, and also sufficiently to accommodate a number of blades 24, 25, which are inserted between the plies of 40 work-web, and upon which are caught sheets of carbon 26 which extend upwardly between the plies of work-web. These blades may point in opposite directions between the plies, especially when the web is fan-folded;

45 and each blade may be supported at its hilt upon one of the web-guiding end-pieces 27 by which the front and rear guide-bars 22 and 23 are connected. The parts 22, 23, 27 taken together may form an eye or guide-bracket which is fixed upon the front of a traveling bar 28, the latter forming a portion of a framework that is secured to the typewriter-carriage 15 to travel therewith; said bar 28 having a roll 29 to run upon a

55 rail 30, and also having a finger 31 to catch under the rail to prevent lifting of the frame. Said frame also comprises upwardly and forwardly extending opposite arms 32, attached by screws 33 to the ends of the bar 28, and connected at their front ends to the ends of the typewriter-carriage 15. The web guiding and holding device therefore travels with the typewriter-carriage.

At Figure 2 is shown the composite web, 60 comprising work-webs 18 and interleaved

carbons 26, all in slack condition, preparatory to the typing of a form upon the web; the slack being preferably in the form of a loop 34 hanging down in front of the guiding and supporting means 22 and behind the 70 platen 11, the slack being sufficient to permit the completion of the line-by-line typing of a form printed on the web as the slack is taken up.

The rail 30 is supported on the rear ends 75 of fixed arms 35, which are spread or separated sufficiently to permit the requisite edgewise travel of the loop of composite web as it conforms with the movements of the paper-carriage 15; said arms 35 being 80 fixed by screws 37 or otherwise to the rear end of the base 38 of the typewriting machine.

At Figure 1 is shown diagrammatically the composite web drawn forwardly far 85 enough to permit the carbons 26 to extend above the printing point 39 at the front of the platen; this position of the web being adjusted or determined by means of a leading-edge gage 40, which is mounted upon a 90 staff 41, which extends upwardly under and beyond a front paper-table 42, the latter extending upwardly and rearwardly from the top front portion of the platen, that is, from 95 its delivery side.

From the Figure 1 position the first typing of a form proceeds line by line, the slack 34 in the composite web being gradually taken up as the typing proceeds; and the typing of the form is finished as soon as 100 or before the slack at 34 is all taken up. At this time the leading edge of the web extends up beyond the gage 40, and the interleaved carbons 26 extend up along the front paper-table 42.

Upon the completion of the first typing of a form (i. e., the second printed form on the web), the platen is rotated backwardly by means of the usual end knob or finger-piece 43, until the requisite slack in the 110 composite web is produced again at 34, or until the interleaved carbons 26 have been retired to a point in rear of the platen or its feed-rolls 14, as at Figure 2. For this purpose, the retraction of the composite web 115 proceeds until the leading edge of the web uncovers a gage or indicator 43^a, at which point the retraction of the web ceases.

This retirement of the plies of work-web and carbons to the Figure 2 position is preparatory to effecting a relative longitudinal shift between said work-plies and the carbons, which is to be effected while the carbons remain stationary. It will be borne in mind that the carbon-sheets are fixed to the 125 blades 24, 25, and that the latter are fixed to the guide-bracket or frame 22 and carriage-bar 28. It is desired to pull the work-webs or plies 18 forwardly while the carbons are stationary until the form on the web, 130

which succeeds the form just typed, is advanced far enough to co-operate with said carbons for typing thereon. In other words, the extent of the relative shifting between carbons and work-webs should equal the depth of a printed form.

Preparatory to effecting this relative longitudinal shift, it is desired to take up the slack in the carbons (which is understood at Figure 2), or tauten them more or less, so that they will not themselves be dragged along or caused to advance when the plies of work-web are pulled forward. To take up the slack of the carbons, there may be used a suitable device, as, for example, a table 44, broadly curved from front to rear, which may be made of sheet-metal, and may be mounted upon a pair of end frames 45, which, by means of a rod 46, are hinged to upstanding arms 47, the latter secured at their lower ends at 48 to the typewriter-carriage 15. The swinging frame may thus comprise the end frames 45, the curved table 44, and the hinge rod 46, and may normally 20 hang (Figures 1 and 2) between the side arms 32 of the rearward carriage-extension, and extend down behind the typewriting machine and the desk; the side arms 32 being connected by a rod or bar 49 at their 25 forward ends, and affording a support against which said curved table-frame may hang.

From the idle position at Figure 2 the table-frame may be swung up by means of 30 a handle 50, connected to one of the side frames 45 thereof, to the position shown at Figure 3, to take up the slack in the composite web.

Prior, however, to movement of this table-frame from Figure 2 to Figure 3 position, the work-webs 18 are clamped to the front paper-table 42, to prevent rearward displacement of the work-webs from their position with their leading ends at the gage 43^a. The clamp employed for this purpose comprises a bar 65 forming part of a bail; this bar being affixed to arms 66 fast on a rock-shaft 67. The shaft 67 is journaled in brackets 68 secured to standards or brackets 69 which are unitary with the front paper-table 42. The standards 69 have laterally-offset flanges 70 which rest upon flanges 71 on the side pieces 12 of the carriage, and which are secured to the latter by screws 72. By means of a finger-piece 73 on an arm 74, also fast to the shaft 67, the bar 65 may be swung against the lower front part of the paper-table 42 to clamp the work-webs. A spring 75, connected to the arm 74, and to one of the standards 69, serves to release the work-webs when the finger-piece 73 is released.

At the time, therefore, that the table 44 is swung from Figure 2 to Figure 3 position, the work-webs are anchored forward

of the table 44, but are free to the rear of that table. Further movement of the table 44, from Figure 3 to Figure 4 position, consequently results in the introduction into the machine of a fresh length of work-webs 70 from the container below the bar 23. The table 44, and the movement thereof, are so proportioned that the table in moving from Figure 3 to Figure 4 position advances into the machine one form-length of work-web; 75 and, since at this time the carbons 26 remain stationary or unadvanced, there is effected a shift of the work-webs relatively to the carbons, to cause the carbons to leave the last typed form-section of the work-webs, and 80 to enter the next succeeding untyped form-section thereof. The table 44 therefore serves not only as a means for taking up the slack in the carbons preliminary to shifting the carbons relatively to the work-webs, 85 but also as a means for effecting such shift; and it may perform both of these operations in a single movement from Figure 2 to Figure 4 position. A pin 51 on one of the frames 45 may engage a stop 52 provided 90 on an arm 53 rising from one of the frame-arms 32, to limit the upward stroke of the curved table-frame.

Having so shifted forward the plies of work-web, the operator releases the handle 95 50, and permits the table 44 to drop to the idle position (Figure 2), thus permitting slack to form again at 34. The operator then revolves the platen forwardly, thereby advancing the composite web until it strikes 100 gage 40, Figure 1, thus bringing the carbons to position to co-operate with the types 10, and positioning the new form properly for the reception of the first line of typing; and the typing of the new form then proceeds line by line as before.

Preferably before the typing of a new form begins, the first form may be torn off from the web by means of a knife-edge 58, as indicated at Figure 1, said knife being secured above the front paper-table 42. The latter may have an opening 60 midway of its ends, through which may be seen the staff 41 and the gage 43^a thereon. The leading edge of the web passes up beneath the knife 110 58, or between the same and the front table 42. The first form at the top of the web is wasted, not having been typed. The second form, which is typed, and which now becomes the new top form, remains in the machine until the typing of the second following form is about to begin, whereupon such new top form is torn off by the knife-edge 58. Thus it results that one typed form always remains in the machine, for convenience in manipulating and gaging the work-webs and carbons. The gages may be independently adjustable along the staff.

It will be seen at Figures 3 and 4 that the rear paper-table 13 may be about tangential 130

to the curve or arch of the elevated curved paper-table 44, or at least that the reach of composite web at 56 may be tangential to both the curved table and the platen, thus 5 avoiding at this place the carrying of the composite web over sharp bends or corners, which would tend to cause the carbons to bind between the plies of work-web, and would therefore hinder or prevent the desired relative slipping of the carbons and 10 work-web plies at the described shifting or readjusting operation. The curvature of the table 44 may be very slight, so as to conduce to free slipping between the work-web plies and the carbon-sheets during such shifting 15 operation. It will be seen that at its front end the curved table is preferably in rear of the platen, and preferably above the same, so that the reach 56 of the web need not turn over any sharp corners; the table curving 20 up from its front end, and gradually changing the path of the web by curving backwardly and then downwardly to a point above the stationary guide 22, 23, and being 25 in such relation thereto that the reach of composite web 57 may extend downwardly tangentially from the paper-table and vertically through the guides, so as to avoid turning this portion also of the composite web 30 over any corners. Thus the web may rise from the supply spool or pack, into the typewriting machine at 22 and change its direction of travel gradually upwardly, forwardly and downwardly to the platen, in 35 such a manner that undue friction or binding between the plies of the web may be avoided during the pulling forward of the web for the relative shifting operation.

Only the forward portions of the sheets 40 26 need to be carbonized. The rear portions, upon which no type-impressions ever fall, may be mere blank paper or other flexible material.

The severing knife 58 may be made adjustable to accommodate different lengths of forms, being, for this purpose, connected by screws or fastening devices 62 to arms or brackets 63 extending upwardly from the ends of the front paper-shelf 42, and having 50 slots 64 to accommodate the adjustment of the attaching screws 62, the latter passing through the slots.

Variations may be resorted to within the scope of the invention, and portions of the 55 improvements may be used without others.

Having thus described my invention, I claim:

1. In a web-manifolding typewriting machine, the combination with a revoluble platen, of means at the intake side of the platen for anchoring at their rear ends carbons interleaved with the plies of work-web, a carbon-stripper between the platen and said anchoring means in the form of a lifter 60 movable upwardly from normal idle position

to distend the composite web sufficiently to pull the web-plies forwardly to an extent to strip the carbons to position for the next form on the web; said stripper normally in such position that a loop of composite web 70 forms between said anchoring means and the platen; and a clamp mounted to fasten the leading end of the web preparatory to the stripping operation.

2. In a typewriting machine, a revoluble 75 platen, means for holding a work-web, composed of a succession of forms, and having carbons interleaved therewith, for line-space feed with the platen, means for holding the carbons stationary at their rear ends, the 80 composite web forming a slack or loop which is taken up during the typing of a form, a web-distender for completely taking up the slack in the first part of its stroke, said distender of such size as to be effective during the remainder of its stroke to distend the composite web between the platen and the carbon-holding means to an extent to shift the carbons backward a complete form 85 length along said work-web, and simultaneously to draw from the source of supply another form-length of the work-web, and means to gage the length of the form-length 90 so advanced.

3. In a typewriting machine, a revoluble 95 platen, means for holding a work-web, composed of a succession of forms, and having carbons interleaved therewith, for line-space feed with the platen, means for holding the carbons stationary at their rear ends, the 100 composite web forming a slack or loop which is taken up during the typing of a form, a web-distender for completely taking up the slack in the first part of its stroke, said distender of such size as to be effective during the remainder of its stroke to distend the composite web between the platen and the carbon-holding means to an extent to shift the carbons backward a complete form-length 105 along said work-web, and simultaneously to draw from the source of supply another form-length of the work-web, means to gage the length of the form-length so advanced, and a clamp for holding the leading portion of said work-web during such shifting.

4. In a typewriting machine, a revoluble platen, means for holding work-web, composed of a succession of forms, and having carbons interleaved therewith, for line-space feed with the platen, means for holding the carbons stationary at their rear ends, and a web-distending rocking table for drawing upon the work-web between the platen and the carbon-holding means and of such dimension and movable to such an extent as to be effective to shift the work-web relatively to the carbons equal to a complete form-length 115 along said work-web.

5. In a typewriting machine, a revoluble 120

5 platen, means for holding work-web, composed of a succession of forms, and having carbons interleaved therewith, for line-space feed with the platen, means for holding the carbons stationary at their rear ends, the composite web forming a slack or loop which is taken up during the typing of a form, a web-distending and carbon-stripping pivoted table movable against the composite 10 web between the platen and the carbon-holding means and during the first part of its stroke taking up the slack, and of such dimensions and movable to such an extent as to be effective, in a continuation of the 15 same stroke, to effect a shift of the work-web relatively to the carbons equal to a form-length along the work-web; and a stop engageable with said table to determine the extent of longitudinal shift of the work- 20 web relatively to the carbons.

6. In a typewriting machine, a revolute platen, means for holding work-web, composed of a succession of forms, and having carbons interleaved therewith, for line-space 25 feed with the platen, means for anchoring the carbons stationary by their rear ends, means for supporting the composite web in such wise as to provide a slack or loop in the untyped part thereof when the web is in 30 position for commencement of typing on one of its form-lengths, said slack being sufficient to permit of line-feed of the composite web in the typing of such form-length without pull on the anchorage of the carbons, 35 means for clamping the leading end of the work-web, and a web-distending and carbon-stripping table movable against the composite web between the platen and the anchorage of the carbons for drawing upon the 40 composite web to take up the slack, said table being of such dimensions and movable so far, in a continuation of the same stroke, as to effect a forward shifting of the work-

web relatively to the carbons equal to a 45 form-length.

7. The combination with a revolute platen, of means for holding permanently stationary by their rear ends carbon-sheets interleaved with work-web plies, the composite web forming a slack or loop which is taken 50 up during the typing of a form, a web-distending and carbon-stripping curved table movable to take up the slack, said table of such dimensions and mounted for such a further movement, as to be effective 55 to distend the composite web to effect a relative shifting of said work-web and carbons equal to a form-length, means being provided to connect the work-web to the platen independently of the carbons during 60 such shifting, gage means for locating the leading edges of said work-web prior to the shifting operation, and means for determining the extent of shift.

8. The combination with a revolute platen, 65 of means for holding permanently stationary by their rear ends carbon-sheets interleaved with work-web plies, the composite web forming a slack or loop which is taken 70 up during the typing of a form, a web-distending and carbon-stripping curved table movable to first take up the slack, and then, upon further movement, to distend the composite web to effect a relative shifting between said work-web and the carbons, 75 means to connect the work-web to the platen independently of the carbons during such shifting, a gage for locating the leading edges of said work-web preliminary to the shifting operation, a second gage against 80 which to gage the leading edge of said work-web to bring the first line of typing of the fresh forms to the printing line, and means for determining the extent of shift of the web relatively to the carbons.

BURNHAM C. STICKNEY.
